ENGINE STARTING APPARATUS

Romeo M. Nardone, East Orange, N. J., assignor
to Eclipse Aviation Corporation, East Orange,
N. J., a corporation of New Jersey

Application April 4, 1934, Serial No. 718,994
Renewed November 7, 1936

12 Claims. (Cl. 123—179)

This invention relates to engine starting apparatus and more particularly to starters of the inertia type.

Such starters have commonly utilized a light inertia member, or flywheel, which is actuated by either manual or power means to a very high speed so as to store energy therein, the energy thus stored being then transmitted to a driven or engine engaging member through a reduction gear train. The use of a yieldable driving connection, such as a friction clutch, between the flywheel and the driven member has usually been included in order to protect the mechanism of the starter in case of overloads or backfiring of the engine being started.

The maximum load which can be transmitted by the starter mechanism has a predetermined value, dependent upon the capacity of the clutch; nevertheless, the starter parts are sometimes damaged before the rotating driven member can be fully and completely meshed with the stationary engine member. In fact, with the present constructions, it is practically impossible to obtain complete mesh before load transmission begins, and sometimes when it is attempted to engage the rapidly rotating driving member with a rotatable member of a large engine to be started while the latter is at rest, only the ends of the teeth of the engaging member become meshed, and there not being sufficient metal to take up the load, distortion or breaking of the teeth occurs.

It is therefore one of the objects of the present invention to provide a novel engine starter of the inertia type in which the driving member may be fully engaged with the rotatable member of the engine to be started without transmitting any load therebetween, and the full load may subsequently be gradually applied, the full faces of the engaged teeth taking the stress without distortion or breaking.

Another object is to provide an engine starter which is rugged and strong enough and of sufficient capacity, to start a reasonably high compression engine in a dependable and efficient manner without requiring a structure of excessive size, weight, or cost of manufacture.

Another object is to provide an engine starter of the inertia type embodying a high speed flywheel of considerable mass, and novel means for effecting movement of the engine engaging or driven member to engine engaging position during the first stage of the flywheel's acceleration.

A further object is to provide a novel engine starter wherein the driven member of the starter may be moved into cranking engagement with the

engine to be started at a time when the former is subject to little or no driving torque, the driving connection between said member and its source of energy being adapted to yield after said movement has been completed, and to continue to yield while the driving energy is being cumulatively stored in the driving element of the starter.

These and other objects will appear more fully from a consideration of the detailed description of the invention which follows. Although only one embodiment of the present invention is described and illustrated in the accompanying drawing, it is to be expressly understood that the drawing is for the purpose of illustration only, and is not to be construed as a limitation of the scope of the invention, reference being had for this purpose to the appended claims.

In the drawing:

Fig. 1 is a longitudinal sectional view of one embodiment of the present invention; and

Fig. 2 is a transverse sectional view along the line 2—2 of Fig. 1.

Referring to the drawing, reference characters 5 and 6 designate two sections of a built-up housing separated by a transverse partition 7 secured thereto by suitable fastening means 8 and centrally apertured to receive bearing means 9 constituting one of the supports for the transmission mechanism connecting the motor 11 and the driven member 12 which as shown is in the form of a pinion slidable upon a supporting shaft 13 into engagement with a gear 14 shown as integral with the flywheel 15 of the engine to be started. As shown, the driven end of the transmission mechanism including the engine engaging pinion 12 is housed within the section 5 and the latter is in turn supported on the frame 17 constituting part of the engine crank case, suitable supporting means being indicated at 18. Secured to the shaft 13 is a sleeve 21 journaled in a bearing 22 secured in the housing section 5 as indicated at 23, the said sleeve 21 being flanged at one end as indicated at 24 and coarsely threaded at its opposite end as indicated at 26, the threading corresponding to that of a nut 27 locked in position upon a barrel or cup-shaped element 28 by suitable means such as the locking ring 29. As shown, the barrel 28 has portions of its cylindrical surface cut away at one end to receive correspondingly spaced radial projections on the nut 27 whereby rotation of the latter is communicated to the former and a drive is thus transmitted to the pinion 12 at which the forward end 31 of the barrel is rigidly connected, as indicated at 32. A suitable nut 33 adjustably fixed to the shaft 13 as

by threads 38 limits the forward threading action of the nut 27 upon the screw threads 26, in conjunction with an interposed compression spring 39, one end of which abuts a washer 41 bearing against the lateral surface of the nut 27 and the opposite end of which engages a seating rim 42 on the stop nut 37. This seating rim 42 also receives a second compression spring 44, the opposite end of which bears upon the forward end 31 of the barrel 28 and takes up shock of disengagement of the pinion 12, upon starting. When the initial rotation of shaft 13 imparts a threading action to the nut 27, it, in conjunction with the rotation restraining effect of the friction exerting springs 48, insures a forward movement of the barrel 28 and hence an engagement of the pinion 12 with the gear 14 prior to any appreciable rotation of any of the parts referred to.

20 In order to secure the meshing action just described in response to the first rotary movement of the armature shaft 51 of the motor 11, but at the same time to delay the actual transmission of driving torque to the engine member 15 until after the motor has been energized for a period sufficient to store a reserve supply of kinetic energy, an inertia member 53 in which such energy may be stored is fixed, as indicated at 25, to the armature shaft 51, and said inertia member 53 is provided with a tapered periphery 59 adapted to be engaged by a correspondingly tapered friction shoe 61 secured, as indicated at 30, to the annular rim 63 of a clutch member 64 having a hub 66 splined or otherwise suitably secured to an intermediate shaft 67 journaled in the previously described bearing 9 and terminating in a pinion 68 adapted to mesh with a plurality of planetary pinions 69 received in a supporting cage 71 drivably connected by suitable pins 72 to the flange 24 of the pinion actuating sleeve 21. A fixedly held internally toothed annulus 77 constitutes the reaction member with which the planetary elements 69 mesh in their planetary movement about the central pinion or sun gear 68. A compression spring 81 bears against the clutch member 64 at one end and is received within an annular pocket 83 in a collar 84 which, in conjunction with a second collar 85 and the interposed 40 thrust members 86 and a retaining ring 87 secured to the hub 66 as shown, completes the clutch controlling assembly. The friction between flywheel surface 59 and the shoe 61 of the clutch member 64 insures transmission of sufficient turning effort through said engaged friction surfaces to impart the necessary rotary movement to the driven sleeve 21 to insure completion of the meshing action of the pinion 12 as previously described. When such meshing action is completed, however, the inertia of the member 14 resists further rotation of the entire transmission, including the clutch member 64, and the flywheel 53 will accordingly proceed to slip freely within shoe 61 and accelerate to high speed in response to the continued energization of the motor. When this accelerating process has proceeded to the point considered sufficient by the operator, the clutch actuating rock shaft 91 is turned in its bearings 93 and 94 formed in 50 the housing section 6, and best shown in Fig. 2, a suitable lever 96, adapted to be actuated by the operator, being provided to secure such rocking of the shaft 91. This rocking movement is communicated to the clutch actuating collar 85 by suitable arms 97 having rounded ends 98

adapted to bear against the lateral surface of the outer collar 85 and thus through the agency of the thrust member 86 and the inner collar 84, exerts a pressure upon the spring 81 which is in turn communicated to the clutch elements 64 and 61 to cause transmission of driving torque 5 from the now energized flywheel 53 to the now engaged pinion 12. A stop may limit the movement of arms 97, if desired. For this purpose each arm 97 has an extension 98 engageable with a boss 99 of casing wall 7.

When the engine has been started by the torque thus transmitted to the engine flywheel 15, the resulting acceleration of the pinion 12 to a speed beyond that of the starter driven sleeve 21 causes the nut 27 to be reversely threaded back to the position indicated in Fig. 1, and this backward movement draws along the barrel 28 and the pinion 12 by reason of the connection constituted by the element 20. Meanwhile the release of the lever 96 permits the spring 81 to return the collar 84 into engagement with the retaining ring 87, thereby relieving the pressure on spring 81. However, the mere contact between surfaces 84 and 86 is sufficient to maintain a light frictional engagement between the elements 61 and 59 so that rotation is imparted through the gear train to member 21, to cause meshing of the pinion 12 upon the next starting operation. The friction of bearing sleeve 66 may also assist in insuring such initial rotation for meshing purposes.

There is thus disclosed a starter of the inertia type in which a high speed flywheel of considerable weight has been combined with a novel transmission mechanism in such a manner that the energy stored in the flywheel may be applied to a rotatable member of an engine to be started without danger of injury to any of the parts of the starter. This result is obtained by the provision of novel means for controlling movement of the driven member into cranking engagement, whereby said engagement may be effected when the driving member is subject to little or no driving torque. By the use of the 40 novel clutch control, the driven member of the starter may be engaged with the engine member without any danger of injury to the teeth of the engaging jaws, and the energy stored in the flywheel may thereafter be gradually transmitted to the driven member after the latter has become engaged with the engine member. Moreover, under favorable conditions, as in summer weather, when starting may be accomplished with the exertion of comparatively little energy, 50 it is possible to convert the unit into a direct-cranking starter by simply throwing arm 96 to apply full pressure to clutch 61 at the out-set, rather than waiting for the flywheel 53 to be first accelerated. This possibility increases the 55 usefulness of the invention.

It will be obvious that the invention is not limited to the form shown in the drawing, but is capable of a variety of mechanical embodiments. Various changes, which will now appear to those skilled in the art, may be made in the form, details of construction, and arrangement of the parts without departing from the spirit of the invention, and reference is therefore to be had to the appended claims for a definition of the limits 70 of the invention.

What is claimed is:

1. In combination, a part adapted to engage and crank an engine member, a flywheel, a clutch of limited torque transmitting capacity 75

permanently engaging said flywheel, and means drivably connected with said clutch to translate the initial rotary movement of the clutch into an engine engaging movement of the engine engaging part.

5 2. In combination, a part adapted to engage and crank an engine member, a flywheel, a clutch of limited torque transmitting capacity permanently engaging said flywheel, and means drivably connected with said clutch to translate the initial rotary movement of the clutch into an engine engaging movement of the engine engaging part and means for limiting the pressure of said clutch against said flywheel to an amount insufficient to prevent acceleration of said flywheel following such engine engaging movement and prior to any substantial rotation of said engine engaging part.

10 3. In combination, a part adapted to engage and crank an engine member, a flywheel, a clutch of limited torque transmitting capacity permanently engaging said flywheel, and means drivably connected with said clutch to translate the initial rotary movement of the clutch into an engine engaging movement of the engine engaging part and means for limiting the pressure of said clutch against said flywheel to an amount insufficient to prevent acceleration of said flywheel following such engine engaging movement and prior to any substantial rotation of said engine engaging part, and manually operable means for increasing the torque transmitting capacity of said clutch.

15 4. In combination, an engine engaging member, a flywheel, a clutch of limited torque transmitting capacity permanently engaging said flywheel, and means including said clutch to translate initial rotary movement of the former into an engine engaging movement of the engine engaging member.

20 5. In a device of the class described, the combination with an engine engaging member of an inertia member, a clutch permanently engaging said inertia member, means for rotating said inertia member to store energy therein, means independent of and distinct from said clutch to cause movement of said engine engaging member to engine engaging position in response to operation of said rotating means, said independent means comprising a sleeve frictionally engaging said rotating means, a shaft surrounding said sleeve, and means drivably connected with said shaft to translate the rotation of said sleeve into an engine engaging movement of said engine engaging member.

25 6. In a device of the class described, the combination with an engine engaging member of an inertia member, means for rotating said inertia member to store energy therein, means independent and distinct from said inertia member to cause movement of said engine engaging member to engine engaging position in response to operation of said rotating means, said independent means comprising a friction exerting sleeve surrounding one end of said rotating means and drivably related to said engine engaging member.

30 7. In a device of the class described, the combination with an engine engaging member of an inertia member, means for rotating said inertia member to store energy therein, means independent and distinct from said inertia member to cause movement of said engine engaging

35 member to engine engaging position in response to operation of said rotating means, said independent means comprising a gear train and a sleeve frictionally connecting said rotating means with said gear train.

40 8. In a device of the class described, the combination with an engine engaging member of an inertia member, a shaft extending through said inertia member and permanently secured thereto, means to rotate said shaft and inertia member to store energy in the latter, and means drivably connecting said inertia member and shaft with said engine engaging member, said last named means including a part frictionally engaging said inertia member, a second part frictionally engaging one end of said shaft, and a second shaft rotatable with both said frictional engaging parts.

45 9. In an engine starter, the combination with high and low speed shafts, of a gear train connecting said shafts, an engine engaging member movable axially along said low speed shaft, means to transmit axial thrust to said engine engaging member, and thereby cause its movement into engine engaging position, pre-set means for yieldingly transmitting torque, up to a limited capacity, from said high speed shaft to said low speed shaft, and removably controlled means for varying the effectiveness of said pre-set means at any selected stage of the starting process.

50 10. In an engine starter, the combination with high and low speed shafts, of a planetary gear train connecting said shafts, and including planets mounted on axles integrated with one end of said low speed shaft, an engine engaging member movable axially along the other end of said low speed shaft, means including a spring coiled about said low speed shaft to transmit axial thrust to said engine engaging member, and thereby cause its movement into engine engaging position, and pre-set means for yieldingly transmitting torque, up to a limited capacity, from said high speed shaft to said low speed shaft, and remotely controlled means for varying the effectiveness of said pre-set means at any selected stage of the starting process.

55 11. In a device of the class described, the combination with an engine engaging member of an inertia member, means for rotating said inertia member to store energy therein, means including a part engageable with said inertia member to cause movement of said engine engaging member to engine engaging position in response to operation of said rotating means, and means carried by said last-named means and tending to maintain the latter effective as a driving connection during the process of storage of energy in said inertia member.

60 12. In a device of the class described, the combination with an engine engaging member of an inertia member, means for rotating said inertia member to store energy therein, means including a part engageable with said inertia member to cause movement of said engine engaging member to engine engaging position in response to operation of said rotating means, and means disposed concentrically of said last-named means and tending to maintain the latter effective as a driving connection during the process of storage of energy in said inertia member.
